UNITED STATES PATENT OFFICE.

RAYMOND A. COLE, OF WORCESTER, MASSACHUSETTS, ASSIGNOR TO NORTON COMPANY, OF WORCESTER, MASSACHUSETTS, A CORPORATION OF MASSACHUSETTS.

GRINDING MACHINE.

Application filed January 5, 1923. Serial No. 610,926.

To all whom it may concern:

Be it known that I, RAYMOND A. COLE, a citizen of the United States of America, residing at Worcester, in the county of Worcester and State of Massachusetts, have invented certain new and useful Improvements in Grinding Machines, of which the following is a full, clear, and exact specification.

My invention relates to a grinding machine and more particularly to a mechanism for traversing and rotating the work.

In grinding the external cylindrical surfaces of such articles as spindles which have portions of reduced diameter, it is necessary, in order to remove one piece of work and insert another in the machine, to feed the wheel away from the work, move the work axially to remove it from contact with the grinding wheel and to stop the work rotation. These various operations require the expenditure of effort, thought and time on the part of the operator and so cut down the production of the machine to a considerable extent.

It is the main object of this invention to provide a mechanism which permits the two movements required to stop and start the work rotation and to traverse the table to be combined in a single operation or which permits them to be carried out independently.

With this and other objects in view as will be apparent in the following disclosure, my invention resides in the combination of parts set forth in the specification and covered by the claims appended hereto.

In the drawings, in which like reference numerals indicate like parts:

Figure 1 is a front elevation of a grinding machine embodying my invention;

Fig. 2 is a fragmentary sectional view showing the connection of the work traversing hand wheel with the work table; and

Fig. 3 is an enlarged sectional view of the hand wheel.

This invention, while of broader utility, is particularly applicable to the grinding machine construction shown in the patent to Charles H. Norton, No. 762,838, dated June 14, 1904. A grinding machine of this type comprises a base 10 having a work carrying table 11, mounted for reciprocation thereon past the peripheral surface of a power driven, rotating grinding wheel 12.

The work is mounted for rotation on centers 13 and 14 and is driven by a suitable driving mechanism mounted in the headstock 15 and driven by a belt 16 from an overhead drum 17. This drum is driven by a tight pulley 18 keyed thereto by means of a belt 19 which may be shifted to a loose pulley 20, mounted to rotate freely on the same axis as the drum 17, in accordance with well known construction. A suitable belt shift mechanism may comprise a shifting yoke 21, engaging the belt and operated by the bell crank lever 22 pivotally mounted on the fixed support which carries the drum 17. This bell crank lever 22 is turned about its pivot by means of the rod 23, which projects downwardly behind the grinding machine and is connected by suitable linkage with a hand operated lever on the front for manual control of the driving belt. The drum is, in the present illustration, mounted on a standard 25 and carried in suitable bearings 26 and 27 mounted on the upper portion of the standard, as is well known in this art.

In order to reciprocate the table on which the work is mounted, I may employ various constructions, but preferably provide the underside of the table with a rack 30, located between the V and flat ways 31 and 32, on which the table is mounted. This rack is reciprocated by means of a gear 34, mounted on the shaft 35, which is supported in suitable bearings located on the machine base. This shaft 35 may be rotated manually by the hand wheel 36, mounted on a short shaft 37, which has a pinion 38 on its rear end in mesh with another pinion 39 on the shaft 35, whereby rotation of the hand wheel 36 will turn the gear 34 and move the table.

The machine is provided with suitable mechanism 40 for feeding the wheel toward and from the work, which may be constructed in any suitable manner, such as is shown in the prior patent to Norton. The table may be properly positioned with the aid of adjustable dogs 41 and 42, located in a T slot 43 on the side of the machine, which are adapted to engage a stop pin 44, mounted on the machine base.

In order to cut down the number of manual operations required to take out a piece of work, insert a new one and start the machine into operation, I provide a mechanism for connecting the table traverse with

the belt shifting mechanism so that by a single manual operation the work may be moved to a new position out of contact with the grinding wheel and the work rotation 5 simultaneously stopped. To this end, I provide a device for connecting the rod 23 with the hand wheel 36, and one embodiment of my invention may comprise the construction shown in the drawings. As 10 there illustrated, the rod 23 is connected to a bell crank device 45, which is mounted on a shaft 46 carried on the machine base and so constructed that motion may be transmitted to the rod 23 from a link 47 pivotally connected thereto. The other end of 15 this link is pivotally connected to a hand operated device mounted to rotate about the axis of the wheel 36. This device may comprise a ring 49 mounted on an annular 20 slide way on the back side of the hand wheel 36 for rotary movement relative to the hand wheel. A hand lever 50 is fixed to the ring 49 and the link is so located on the ring, substantially tangential thereto, 25 that rotation of the ring causes a consequent movement of the link 47 and the belt shifting rod 23. This ring 49 may be suitably held in place by means of a clamping 30 ring 51 screwed to the back side of the hand wheel 36.

In order to connect the hand wheel 36 with the ring 49, I provide a pin 55 slidably mounted in a hole in a boss 57 on the hand wheel 36. The ring 49 is provided 35 with a groove 58 on its internal face, or preferably a series of grooves formed around its inner perimeter so that the ring might be clamped to the wheel in any suitable position relative thereto. The pin 55 40 is, therefore, adapted to be pushed into contact with the groove 58 in the ring or drawn outwardly so that the inner end of the pin is free from engagement with the ring, thus permitting the latter to rotate relative to 45 the hand wheel.

In order to hold the pin in either a locking or unlocked position, I provide any suitable mechanism such as a spring pressed plunger 50 60 slidably mounted in a hole in the boss 57 arranged at right angles to the hole 56. Two annular grooves 61 and 62 are provided on the pin 55 so that the locking pin 60 may engage one or the other and thereby hold the pin 55 in engagement with the ring 49 or prevent engagement therewith. So that the spring pressed plunger may be operated easily, the ridge between the grooves 61 and 62 is so shaped as to permit the end of the pin 60 to slide easily from one groove to the other as the pin 55 is pulled out or pushed in.

The locking pin 60 is mounted in an adjustably positioned screw threaded collar 64, which may be turned relative to the boss 57 to adjust the tension of a small coil spring 65 which surrounds the pin 60 and engages a shoulder thereon and the under face of the adjustable collar. A locking nut 66 may be provided to hold the pin adjustment 70 as desired.

It will, therefore, be seen that by pushing the pin 55 into contact with the ring 49, the wheel and ring are thereby locked together so that upon movement of the hand lever 50, the hand wheel 36 is caused to move the table 11 and at the same time, the ring 49 moving with the hand wheel operates to shift the belt 19. This construction permits one to disconnect the work rotating and table traversing mechanisms and operate the 80 machine also in its normal manner.

What I claim as new and desire to secure by Letters Patent, is:

1. A grinding machine comprising a reciprocable work supporting table, a power driving mechanism to rotate the work, a manual control therefor, a manually operable device to reciprocate the table, and connections including a releasable locking device between said control and said table operating device which are so constructed and arranged that movement of the table may control the power or the power may be controlled and the table operated independently of each other.

2. A grinding machine comprising a reciprocable table, work supports thereon, a power mechanism to rotate the work, a manually operable hand wheel connected to reciprocate the table, a manually controllable device to connect and disconnect the power from the work, which includes a member mounted concentrically with said hand wheel, and means to connect or disconnect said hand wheel and member.

3. A grinding machine comprising a reciprocable work supporting table, a mechanism to reciprocate the table including a hand wheel, power driving mechanism to rotate the work on said table, a manually controlled device to start and stop the power driving mechanism including a member rotatable concentrically with said hand wheel, releasable means to connect said hand wheel and member whereby movement of the table controls the power and means to lock said releasable connecting means in either an operative or inoperative position.

Signed at Worcester, Massachusetts, this 2nd day of Jan. 1923.

RAYMOND A. COLE.
